(57) **CLAIM**

We claim the ornamental design for an above ground pool, as shown and described.

DESCRIPTION

FIG. 1 is a perspective view of a first above ground pool; FIG. 2 is a front elevational view thereof, wherein the rear is a mirror image of the front; FIG. 3 is a side elevational view thereof, wherein the opposite side is a mirror image of this side; FIG. 4 is a top plan view thereof; FIG. 5 is a bottom plan view thereof; FIG. 6 is a perspective view of a second above ground pool; FIG. 7 is a front elevational view thereof, wherein the rear is a mirror image of the front; FIG. 8 is a side elevational view thereof, wherein the opposite side is a mirror image of this side; FIG. 9 is a top plan view thereof; FIG. 10 is a bottom plan view thereof; FIG. 11 is a perspective view of a third above ground pool; FIG. 12 is a front elevational view thereof, wherein the rear is a mirror image of the front; FIG. 13 is a side elevational view thereof, wherein the opposite side is a mirror image of this side; FIG. 14 is a top plan view thereof; and, FIG. 15 is a bottom plan view thereof.

(Continued)

The phantom lines in FIGS. 1-15 represent unclaimed portions of the pool and form no part of the claimed design.
